UNITED STATES PATENT OFFICE.

ANNE JACOBUS MATHYS AUGUST RIDDER VAN DER DOES DE BIJE, OF THE HAGUE,
NETHERLANDS.

FURNACE.

Application filed August 15, 1923. Serial No. 657,591.

This invention relates to improvements in furnaces, and particularly to improvements in furnaces having a mechanical stoker of the type patented to me by Letters Patent 5 of the United States of America, No. 1,314,- 389, and comprising as essential elements a grate portion having a large draft capacity, another grate portion having a much lower draft capacity, an underfeed device adapted to advance the fire bed on the grate portion with a large draft capacity, and means for supplying supplementary air to the combustion chamber above the fire bed.

The principal object of my present invention is a furnace grate of this type which is of a more simple construction.

In the furnace described in the said patent specification means are provided for discharging the ashes and clinker from the grate at the rear end thereof. Meanwhile it has proved in practice that ash traps in the fire bottom give rise to leakage of air from the ash pit to the fire bed. This air may seriously impair the efficiency of the 25 furnace as it enters the fire bed where the draft capacity of the grate should be very low or zero.

Now I have found that the ashes in a furnace of said type bake or cake to clinker and that this clinker may from time to time be withdrawn by a fire door in the furnace front. Furthermore I have found that this simple arrangement also allows of the provision of an unsymmetrical grate, in which the area with a large draft capacity is disposed at one side of the grate. The clinker in such a furnace automatically moves to a part of the grate whence it can be removed through a door in the front of the furnace by means of an ordinary fire hook or rake.

In the accompanying drawings—

Figure 1 is a vertical section of a furnace according to the invention taken on the line 1—1 of Fig. 2. Surrounding parts have not been shown as these are not essential;

Figure 2 is a plan view;

Figure 3 shows the front of the furnace; and

Figure 4 is a cross sectional view of the grate, on line IV—IV in Figure 1.

As shown the furnace is adapted to be inserted into a flue of a boiler, and constituted by a bar section 5 having a large passage for the air, and by a portion 9 provided with small blow holes for the air which is forced

into the space below the fire bottom, said space being enclosed by a curved plate 6, part of the fire bridge casting 7, and by the front ash pit door 8. The apertures in the grate portion 9 are so dimensioned and so distributed over said portion that the coal receives a suitable quantity of air. It has been found that coal after having lost its gaseous constituents and after being converted into coke should be burnt down more slowly if a high efficiency is to be attained, so that at the end and at the sides of the fire bottom hardly any primary air should be fed to the fire bed.

The front of the furnace is formed by a cast iron frame 10 supporting a coal hopper 11 and provided with a door 12 for preventing coal from dropping from the furnace while raking the grate, a fire door 13 with a small sight door there above and the poking door 14, the ash pit door 8, and a connection 15 connected with the air tube 16, the latter being equipped with a valve operated by means of a handle 17.

Arranged in the upper part of the casting 10 is a cavity with a nozzle 18 for blowing secondary combustion air over the fire bed 19. The air is fed into said cavity through a tube 20 provided with a regulating valve 21 and branched from tube 16.

The frame 10 also serves to support a frame 22, mounted in which is a reciprocating gear (not shown) driven by a pulley 23 keyed on a shaft 24 and imparting rotary movement to a screw spindle 25 in either the one or the other direction so as to move the ram or plunger 26 forward or backward. The ram 26 is stepped as at 27. During the return stroke of the ram fresh coal from the hopper 11 falls by gravity on the ram in front of said step, and during the forward stroke of the ram this coal is pushed under the fuel 19 already on the fire bottom. The end portion 28 of the ram is bevelled at one side as at 29, so that during the forward stroke of the ram the greater part of the coal and clinker resting on the fire bottom is carried forward, the smaller part being pushed sideways so that the fuel is uniformly distributed over the fire bottom.

Experience has shown that a cast iron ram can operate for a long time before it requires renewal. As it is not necessary for the end portion 28 to be completely withdrawn from the fuel on the fire bottom, the

travel of the ram may be reduced to a minimum. The movement of the ram through the fuel is of extreme importance because the fuel is thereby disturbed in its lower layers

5 so that blow holes in the fire close themselves.

The secondary air, which is injected in a manner similar to what is known in ordinary furnaces for the purpose of smoke combustion, mixes up with the gases which 10 are produced from the coal immediately after the coal has been fed onto the fire bottom, and this mixture of combustible gases and air contacts with the hot flames above the bar section 5 so that it is burnt very 15 completely. The air, which is not used for burning the gases is consumed by the red hot coke distributed over the rear end and the side portions of the fire bottom. This 20 system of burning fuel has given very satisfactory results.

The simple construction of the furnace renders it fit for use in the flues of ordinary Scotch marine boilers and the like.

During the operation of the furnace a certain quantity of clinker accumulates at the 25 end and another quantity collects upon the plate portion of the fire bottom. These quantities depend upon the quality of the coal; with fuel of ordinary quality the clinker should be removed about every eight or 30 twelve hours. The fact that the fire bottom is flat facilitates the discharge of the clinker.

The simple construction of the fire bottom

is a guarantee for an exact distribution of the air through the apertures in every part 35 of the fire bottom without any unexpected by-passes.

I claim:—

1. A furnace fire bottom of substantially flat form having an area with a large draft 40 capacity and an adjacent area with a much lower draft capacity, in combination with a feed ram arranged at one side of the longitudinal axis of the furnace and adapted to advance the fire bed on the area with a 45 large draft capacity, means for supplying supplementary air above the fire bed, a fire door disposed in the furnace front at the wide side thereof in respect to the ram, and a poking hole in the furnace front at the 50 other side thereof in respect to the ram.

2. In a furnace, a fire bottom including a bar grate portion and a plate grate portion, both grate portions in their entirety being arranged in the same plane, a feed ram 55 slideable over the bar grate portion of the fire bottom and a nozzle arranged above the fire on the fire bottom for supplying supplementary air above the fire bed.

3. A furnace as claimed in claim 2 characterized by the arrangement of the bar grate portion and ram at one side of the center of the fire bottom.

In testimony whereof I affix my signature,
ANNE JACOBUS MATHYS AUGUST
RIDDER van der DOES de BIJE.
